UNITED STATES PATENT OFFICE

2,516,557

CONVERTIBLE NURSERY SEAT

John D. Frazee, Glastonbury, and William H. Russell, Talcottville, Conn.

Application September 1, 1948, Serial No. 47,176

4 Claims. (Cl. 155—131)

1

This invention relates to improvements in convertible nursery chairs. The principal purpose of the invention is to provide a portable, rugged and attractive nursery chair which is easy and economical to manufacture; which may be applied to the conventional bathroom seat for use by infants, or attached to the back of the front seat of a motor vehicle as an infant's car seat; and which comprises a removable and foldable seat member adapted to be easily carried about and used separately as an infant's toilet seat in public rest rooms or elsewhere.

A more specific object of this invention is to provide a convertible nursery chair having a seat frame adapted removably to receive a separable toilet seat which, after removal, is foldable upon itself to relatively small compass so that it may be conveniently carried in a bag or small package.

Another particular object is to equip the nursery chair with a foldable back member hinged to the seat frame and adapted to be latched in folded upright position to serve as a back rest, or to be extended and swung downwardly onto the toilet seat to serve as a cushioned, unapertured seat member when the chair is used as a car seat.

Other novel features and advantages of the improved nursery chair will become apparent from the following description of the recommended embodiment of the invention illustrated in the accompanying drawings, and will be pointed out in the appended claims. It will be understood, however, that the structural details of the chair herein illustrated and described may be varied without departing from the essence of the invention as defined in the claims. In the drawings,

Fig. 1 is a plan view of the assembled nursery chair, as arranged for use on a conventional bathroom seat, a foot rest of the chair being broken away;

Fig. 2 is a front view of Fig. 1, with a portion of the foot rest broken away;

Fig. 3 is a side view looking to the right of Fig. 1;

Fig. 4 is a section on line 4—4 of Fig. 1, showing the chair converted for use as a car seat, and provided with a removable support adapted to hook over the permanent front seat of the vehicle;

Fig. 5 is a perspective view of the detached, foldable toilet seat; and

Fig. 6 is a perspective view of the support for the car seat.

In the particular form chosen for the purpose

2

of illustration, the convertible nursery chair comprises essentially a seat frame having parallel wooden side members 11, a front cross piece 12 consisting of a flat metal bar attached to the under side of said members, and a back cross piece 13 consisting of a metal angle bar fastened to and beneath the rear ends of the side members; a foldable, combination back and seat rest 14 (Fig. 1), consisting of the part 15 pivotally connected to the rear margins of the sides 11, as by hinges 16, and the extension part 17 pivotally connected to the outer edge of part 16, as by hinges 18; a removable toilet seat 19 (Fig. 5), consisting of similar side members 20 and 21, pivotally connected at their abutting rear portions, as by a hinge 22, and normally resting on the bars 12 and 13 between the sides 11.

Metal arm brackets 23 of inverted U-shape are suitably attached to said sides 11, and support wooden arm rests 24 which carry a cross belt or strap 25. Metal side brackets 26 are adjustably mounted on the outer edges of the frame sides 11, and support at their free forward ends a foot rest 27.

For use as a juvenile bathroom chair, the seat frame is preferably equipped with depending attachments which serve to hold the chair rigidly in place on a conventional adult bathroom toilet seat (not shown). A pair of rubber-covered front lugs or clips 28 are fixedly attached to the front bar 12, and a rubber-covered hook member 29 is slidably attached to the rear bar 13, as by a loop-like bracket 30. The front clips and rear hook are preferably flexible and may be bent, if necessary, to fit the adult seat. In this usage, the parts 15 and 17 of the back rest 14 are folded together in upright position, as shown in Figs. 1 to 3, and held in such position by swinging latch members 31 which have hook portions engaging on bolts 32 passing through the rear legs of the arm brackets 23, and removably secured by wing nuts 33. Loosening of the wing nuts frees the latches, which are pivoted to the back part 15, and permits the back rest to be extended forwardly, as indicated by dotted lines in Fig. 4, and to rest flatwise on the toilet seat 20, 21 to provide a cushioned seat, the hinged parts of the back rest being suitably upholstered. Other forms of latching members may be employed, if desired.

The outer side edges 34 of the removable toilet seat are preferably beveled or inclined downwardly and outwardly, and the inner edges of the frame sides 11 are correspondingly beveled or inclined, so that the abutting edges interlock

to hold the flattened seat in position. The toilet seat 19 is easily removed from the chair seat frame by sliding the seat 19 forwardly a few inches to clear the overhanging back rest, and then folding the parts 20 and 21 on the hinge 22 to disconnect the interlocked edges at 34. The hinged halves of the detached toilet seat may then be folded against each other, so that the folded seat may be carried in a hand bag or the like while traveling, for use on an adult toilet seat in a public rest room, or elsewhere, as aforesaid.

For use as a car seat, the back rest or cushion parts 15 and 17 are unlatched from the arm brackets and swung forwardly to extended position, over the toilet seat 19, or onto the side frames 11, if the seat has been removed, as shown in Fig. 4. A carrier or supporting frame consisting of a pair of metal bars 40 having rubber-covered, hook-shaped upper ends 42, and connected by a cross bar 43 at their lower ends, is adapted to be applied to the back of the front seat of a motor vehicle, in an obvious manner. The bars 40 have a series of corresponding key-hole slots 44 spaced vertically of the supporting frame, and complementary pairs of such slots are adapted to receive the bolts 32 carried by the arm brackets 23, as previously explained. The car seat may thus be removably and adjustably connected to the supporting bars 40 by passing the bolts through appropriate slots 44 and through the apertures of the brackets 23, and then applying and tightening the wing nuts 33 (Fig. 4).

We claim:

1. A convertible nursery chair comprising a seat frame having parallel side members and front and rear cross members attached under said side members, a toilet seat detachably applied to said frame between said side members and on said cross members, the toilet seat having pivotally interconnected side parts whereby the detached seat may be folded upon itself, and the side members and seat parts having slidably interfitting edges whereby the seat may be slid forwardly of said frame.

2. A convertible nursery chair comprising a seat frame having parallel side members and front and rear cross members attached under

said side members, a toilet seat detachably applied to said frame between said side members and on said cross members, the toilet seat having pivotally interconnected side parts whereby the detached seat may be folded upon itself, and the side members and seat parts having slidably interfitting edges whereby the seat may be slid forwardly of said frame, and a back rest having a pair of pivotally connected parts, one of said parts being hinged to the back of said frame, whereby the back rest may be folded to upright position or extended forwardly to rest on said side members and serve as a seat rest.

3. A convertible nursery chair comprising a seat frame, a toilet seat removably applied to said frame, a back rest having pivotally interconnected parts foldable upon each other, and a hinge pivotally connecting one of said parts to the back of said frame, whereby the back rest may be folded upon itself and swung to upright position or, alternatively extended forwardly to rest on said frame and serve as a seat.

4. A convertible nursery chair comprising a seat frame, arm brackets fastened to the sides of said frame, a toilet seat removably applied to said frame, a back rest having pivotally interconnected parts foldable upon each other, and a hinge pivotally connecting one of said parts to the back of said frame, whereby the back rest may be folded upon itself and swung to upright position or alternatively extended forwardly to rest on said frame and serve as a seat, one of said back rest parts having a latch engageable with one of said arm brackets, and means for detachably securing the latch to said bracket.

JOHN D. FRAZEE.
WILLIAM H. RUSSELL.
